SAFETY RAZOR

John Warren O'Mealey, Boston, Mass.

Application January 2, 1940, Serial No. 312,120

3 Claims. (Cl. 30—71)

This invention relates to a safety razor the general object of the invention being to provide a means of adjusting the guard of said razor in relation to the cutting edge of the blade so that any degree from a very light to a very close shave may be obtained while the blade is firmly held at the proper cutting angle at all times. Most razors today are designed to position the blade at but one cutting angle and that angle may or may not be suitable to the beard or skin condition of the user.

The aforementioned adjustability is accomplished by means of a spring-pressed plate operating vertically between the inner lateral sides of the guard member which is made with its middle section channelled to receive this plate as well as the supporting spring. The spring, extending the full length of the plate, operates between the under surface of the plate and the bottom of the channel. The plate may be thus lowered or raised to its original position, i. e., flush with the top sides of the guard channel, under spring tension, the contributing factors and results of which are hereinafter fully described.

Another object of the invention is to make the lower lateral edge of the clamping member or head curve upwardly from the center to the ends, to which curve the blade will conform when positioned for use. This will result in presenting more cutting edge to the face at one time, thus reducing the shaving time and making the blade edge conform better to the facial contours of the user. It also promotes a slicing action as the cutting edge meets the beard.

Another object of the invention is to provide a secondary guard on the head member to the rear of and in alignment with the blade edge and the guard bar, so as to assure the proper shaving angle at all times and to raise a fold of skin between itself and the guard bar. The shaving angle, in the same sense used, should be interpreted as the angle at which the razor is held on the face of the user, shown as line AA on Figure 3 of the drawings. By similar interpretation the cutting angle is the angle to which the blade edge is held in relation to the guard bar.

Another object of the invention is to convex or hollow in an inward curve that portion of the head member between the secondary guard and the lateral edge of the head member to further promote the ripple of skin above referred to.

A further object of the invention is to provide ears or flanges at the ends of the lateral edge of

the head member, said ears being projected in the same plane beyond said edge to the blade corner as a protection against being cut from the side of the blade corner.

Another object of the invention is to provide a saddle of rubber or the like on the spring plate part of the guard member over which saddle the blade is crowned in shaving position by clamping pressure from the head member. This saddle is formed of resilient material that it may function to remove most of the unpleasant vibration and harshness of the ordinary metallic razor.

A further object of the invention is to provide a channel or groove on the studs and shank at the point directly below the head member for the purpose of freeing the blade from all contact with said studs and shank when the blade is crowned to the above point. Should the head member be made of thermoplastic or similar material, it can be seen that the blade is touching no metal parts whatever thereby appreciably increasing the softness and pleasant feeling which is desirable.

Another object of the invention is to provide a shoulder on the studs and a projecting pin on the shank at the same lateral plane in which shoulders and pin engage the top surface of the spring plate simultaneously for the purpose of forcing the plate downward when clamping pressure is applied and preventing undue compression of the rubber saddle.

Another object of the invention is to provide a means for removably holding the rotary member of the handle within the tubular part of the handle so that the parts may be readily separated or handled as a unit. This is accomplished through the use of an internal thread section in the collar member of the handle through which an external thread on the inner end of the rotary member may pass into a clearance void. The rotary member having an undercut section following this thread, must be extended slightly into this void before its internal thread may engage the threaded shank so it may be seen that upon releasing the shank the rotary member is riding free in the handle though it will not disengage itself.

A further object of the invention is to provide means of determining and holding the cutting angle desirable to the user by the application of a series of lettered or numbered recesses on the lower edge of the fixed handle tube into which a cam or projection on the rotating or tightening handle member may slide and be held securely in place under the spring pressure exerted

by the blade and the spring plate when the units are assembled for use. This will permit the user to adjust the parts to the desired cutting angle and retain such adjustment unless intentional force is applied to remove the cam from the groove.

This invention also consists in certain other features of construction and in the combination and arrangement of the several parts to be hereinafter fully described, illustrated in the accompanying drawings and specifically pointed out in the appended claims.

In describing the invention in detail reference will be had to the accompanying drawings wherein like characters denote like or corresponding parts throughout the several views, and in which:

Figure 1 is an elevational view of the improved razor showing the head and guard part in end view with head and spring plate lowered into guard part.

Figure 2 is an elevational view of the upper end of the razor with the head part in side elevation.

Figure 3 is a section on the line 3—3 of Figure 2.

Figure 4 is a section on the line 4—4 of Figure 3.

Figure 5 is a top plan view of the razor.

Figure 6 is a fragmentary view of the blade.

Figure 7 is a top plan view with the top member removed.

Figure 8 is a fragmentary cross sectional view showing a modification of the spring member.

Figure 9 is a view of the outer end of the rotary shank.

In these drawings the numeral 1 indicates the head member or upper clamping member which carries the centrally arranged threaded shank 2 and the studs 3 which pass through the openings in the blade B which is flexible enough to conform to the parts of the razor when clamped between the clamping parts thereof. The shank is formed with a groove 4 and each stud with a groove 5 to prevent these parts from contacting the blade as shown in Figure 4. Each stud is provided with an enlarged part 6 which provides a shoulder at the junction of the large part with the lower part and a pin or projection 7 is carried by the shank and has its underside in the same plane as the shoulders for a purpose to be hereinafter described. The top of member 1 is formed with a comparatively narrow portion to provide the shoulders 8 and the underside of the member 1 is of the usual arcuate shape to provide an upwardly bowed undersurface and from the shoulders 8 the edges of the member 1 are hollowed out to provide the concave surfaces 9. At the ends of each part 9 a flange 10 extends upwardly beyond the concave surface, these flanges retaining the shape of the top and bottom arcs of the head member at their outside edges as will be seen in Figure 1, but their inside edges are beveled to meet the ends of surface 9 as shown at 10' in Figures 2 and 5. These flanges guard the side edges at the corners of the blade and prevent such parts of the blade from inadvertent cutting. Each edge formed by the junction of the part 9 with the under surface of the member 1 is curved as shown at 11 in Figure 2 with its center at the lowest point and the edge curved upwardly from said center to the ends so that said edge is bowed downwardly. This edge causes the cutting edge of the blade contacting it to assume the same curve. The shoulder 8 forms a secondary guard which is in shaving plane

alignment with the primary guard bar 12 at each side edge of the lower clamping or guard member A and said shoulder is curved inwardly as at 3' in conformation with the curved guard edge. As mentioned in the third object of invention the shoulder 8 and the bar 12 assure the proper shaving angle at all times and these two parts raise a fold in the skin between them during the shaving operation so that the blade will easily cut the hairs on this part of the skin.

This member A is carried by the hollow centrally arranged collar 13 which forms part of the handle and the shank 2 of the upper member 1 passes through the collar 13 and the upper face of the member A is formed with the longitudinally extending channel 14 with the bars 12 supported from the side walls of the channeled part by the end members 15 and the central member 16, these bars 12 having their upper outside edges downwardly or inwardly bowed as at 17 to conform to the curved part 11 at each side edge of the part 1. These edges 17 are also rounded as shown.

A plate 18 is located in the recess or channel 14 and has the spring parts 20 connected with the side edges and extending under the plate to engage the bottom of the channel 14 so that the plate is pressed upwardly. This plate has the openings 21 therein for the passage of the shank 2 and the studs 3 as has the member A, and is held against being projected beyond the channel by parts 21 as hereinafter described. Where studs 3 pass through this plate outwardly beveled bushings 23 are attached to the plate for the purpose of securing the member 22. This member 22 of rubber or the like is removably connected with the top of the plate 18 by being stretched over said bushings as shown in Figure 4. The rubber member has an arcuate or convex upper surface to conform to the arcuate lower surface of the top member 1 and at its side edges it is extended so as to project beyond the side edges of the member A but not as far as the bars 12 and said side edges of the rubber member are undercut as shown at 24. This member has openings to engage the above referred to bushings and for the passage of the shank and studs. That part of the member A which has the channel therein has its ends reduced and the ends of the plate 18 are turned downwardly as at 25 to pass through the recesses formed by these reduced ends and then the ends 26 are turned inwardly as at 27 to fit over the reduced ends so as to yieldingly hold the plate in the channel. The upper portions of the reduced ends are beveled as at 28 to permit the ends 27 to be pressed over the same when the plate is placed in the channel. While Figures 3 and 8 show the spring members 20 formed with the plate it is to be understood that other suitable forms of spring means may be placed in the channel to force the plate 18 upwardly.

Figure 8 shows a modification of the spring parts 20' and in this figure the junction of the spring parts with the plate 18' form shoulders which engage under projecting parts or flanges 29 of the member A which extend over the side parts of the channel. Thus the plate 18' is held in position in the channel by these parts which limit its upward movement. When this arrangement is used the end parts 26 and 27 are omitted and the ends of the channel may be closed.

A socket 31 is formed in the collar 13 and a flange 32 extends into the socket and has its inner circumference threaded as shown in Figure

3. A hollow handle 34 is adapted to fit in the outer part of the socket and a shank 35 passes through the hollow handle and has a reduced inner end which is provided with a flange 36 at its end which is threaded to engage the threads 32. The outer end of the shank 35 which projects from the hollow handle 34 is formed with a knurled enlarged part 37 which has a projection 38 thereon for fitting in any one of a number of recesses 39 formed in the outer end of the handle part 34, these recesses being numbered or otherwise marked, as shown in Figure 1, this projection or cam 38 and recesses 39 indicating the different cutting angles to which the razor may be adjusted. As will be seen by placing the threaded flange 36 of the shank 35 in the socket 31 until the flange engages the internal flange 32 and then turning the shank the flange 36 will pass by the flange 32 and then the shank 35 will be movably held to the collar 13, the inner end of the shank 35 having a threaded socket therein for receiving the threaded end of the shank 2 of the member 1 so that by turning the shank 35 the shank 2 with the member 1 is moved toward or away from the part A.

In operating the razor, the blade is positioned over the studs and shank of the head member, the lower member (handled as a unit) is applied to and positioned with the head by means of said studs and shank. The rotor 35 engages the threaded shank 2 and the clamping pressure exerted through the rubber saddle 22 crowns the blade, at which point the stud shoulders and shank pin 7 engage the spring actuated plate 19. The spring means beneath this plate is sufficiently strong to withstand this first pressure but as additional force is exerted by the further turning of shank or rotor 35 this spring allows the entire head section and the plate to be lowered to the guard bars 12. The degree of lowering governs the cutting angle, a variety of which may be obtained, while the blade is always positioned at the correct shaving angle.

To further describe the action of the blade curve, it is apparent that a straight lateral edge when held against a convexed surface can only contact so much of this surface no matter at what angle it is applied. It must be also apparent that if this lateral edge be curved upwardly from its center to its ends and then held at 40 degree angle (the usual shaving angle) on the convexed surface, more of the edge is contacting the surface in proportion to the curve permitted and if drawn downward on this surface a slicing stroke from the center toward the ends of the curved lateral edge is actuated.

The action and purpose of the secondary guard which is in contact with the skin simultaneously with the guard rod and blade is three fold, namely; it keeps the razor at the correct shaving angle at all times; it eliminates the possibility of the blade cutting the face of the user when undue pressure is applied or the razor is held at such an acute angle that the primary guard

leaves the skin and ceases to function protectively; it promotes a ripple of skin between itself and the guard bar thereby allowing the blade edge to cut the hair on a convexed surface which results in an extremely close, fast and non-irritating shave.

It is thought from the foregoing description that the advantage and novel features of the invention will be readily apparent.

10 It is to be understood that changes may be made in the construction and in the combination and arrangement of the several parts provided that such changes fall within the scope of the appended claims.

15 Having described the invention, what is claimed as new is:

1. In a safety razor including upper and lower head parts and means for holding a blade between the said parts in an upwardly bowed position with its cutting edge bowed downwardly, a guard bar at one side edge of the lower head part and spaced therefrom, the adjacent side edge of the upper head part having a thin edge which curves upwardly from its center toward each end, the upper edge of the guard bar being correspondingly curved to align therewith.

2. In a safety razor including upper and lower head parts and means for holding a blade between said head parts with the blade upwardly bowed and with its cutting edge bowed downwardly, a guard bar at one side edge of the lower head part and spaced therefrom, the adjacent side edge of the upper head part having a thin edge which curves upwardly from its center toward each end, the upper edge of the guard bar being correspondingly curved to align therewith, and the upper head part having a shoulder forming portion at one side edge spaced from the thin edge and forming a secondary guard which cooperates with the guard bar for forming a fold of skin, the hairs on which are cut by the blade.

3. In a safety razor including upper and lower head parts and means for holding a blade in an upwardly bowed position between the head parts, with the cutting edge of the blade bowed downwardly, a primary guard bar extending along a side edge of the lower head member and spaced therefrom, the adjacent edge portion of the upper head member having a thin edge which curves upwardly from its center toward each end with the said bar correspondingly curved to align therewith, a secondary guard at said side of the upper head member and spaced upwardly and inwardly from said thin edge, the primary guard bar and the secondary guard acting to form a fold of skin between them, the hairs on which are cut by the blade during the shaving operation, the surface between the last-mentioned guard member and said thin edge being concaved, and flanges at the ends of the concaved part.

JOHN WARREN O'MEALEY.
